UNITED STATES PATENT OFFICE

JOSEPH F. MOODY, OF TULSA, OKLAHOMA

SAFETY-HOOK DEVICE

Application filed May 15, 1929. Serial No. 363,278.

My invention relates to safety hooks such as are used in connection with derricks in the oil fields for engaging the bails of gripping devices, which carry the tubing, casing or drilling apparatus.

Briefly stated, the invention has for one of its more important objects, the provision of a novel and improved device of this character incorporating a latching device which 10 is capable of moving in both directions when released, for facilitating the insertion or removal of the bails from the recess of the device which receives the same.

The invention also contemplates a device 15 of this nature which is very simple in construction, easy to operate, exceptionally strong and durable, and generally of exceeding efficiency in practical use.

The invention resides in certain features 20 of construction, combination and arrangement of the various parts, and in certain modes of operation, all of which will be readily understood and appreciated by those skilled in the art upon reference to the accompanying drawing in connection with the 25 following detailed description.

In the drawing, wherein is illustrated what now appears to be a preferred embodiment of the invention—

30 Figure 1 is a perspective view of a safety hook incorporating my invention;

Figure 2 is a longitudinal sectional view, and

35 Figure 3 is a section on the line 3—3 of Figure 2.

Referring specifically to the drawing in which the same reference characters have been used to designate the same parts in all views, 1 denotes the shank extending from 40 the body 2, which latter is provided with two pairs of opposed ears, 3, 4, extending from one edge of the body and providing extensions of a slot 5 in such edge which commences at the collar 6, which separates the 45 shank 1 from the body 2 and increases in depth in the direction of the opposite end of the body to a point slightly beyond the medial portion of the ears 4, the bottom wall of the slot from this point inclining outwardly at 5^a to the bail receiving recess 7,

which is defined by the hooked end or bill 8. It will be observed that the hooked end of the body portion is offset rearwardly slightly and likewise that the edge walls of the ears 4 lie in a plane substantially transverse to the axis of the body and inwardly of the end portion of the bill 8. 55

The ears 4 are relatively small and are located adjacent the collar or shoulder 6, their function being through pin 10 to pivot 60 the rear end of the trigger or locking member 11, which is located in and extends outwardly from the slot 5 so as to be readily operable by the hand.

The ears 4, as has been intimated, are 65 located adjacent the bill 8 and project slightly outwardly of the end of such bill so as to provide ample bearing for the latch member 13, which is located in the slot at this point and pivoted on pin 14 extending through 70 ears 4. The outer edges of the ears 4 also provide a relatively flat arced bearing surface for the bails in their movement to and from the hook recess.

The trigger member 11 is relatively long, 75 as indicated, and its outer end is relatively widened and provided with a medial recess inwardly of the inner edge extension 11^a, whose end forms a shoulder adapted to engage the heel portion 13^a of the latch 13. It 80 will thus be plain that movement of the latch 13 inwardly into the slot 5 between the ears 4 will be prevented by the engagement of such shoulder or inner end extension 11^a with the heel portion 13^a of the latch element 13. 85

The widened portion of the trigger or locking member 12 is cut back short of the end of portion 11^a to provide a shoulder 11^b to engage the toe portion or shoulder 13^b of the latch member adjacent the outer edges of the ears 4. It is to be noted that the shoulders or portions 11^a, 13^a are at one side of the pivot of the latch element, while the shoulders 11^b, 13^b are at the opposite side. 93

A spring 16 having an arcuate end portion 16^a to embrace the rear end of the trigger or locking member 11 is located in slot 5 beneath the bottom edge of such trigger to normally urge the same outwardly so as to maintain 100

shoulders 11^a, 11^b in engagement with latch shoulders 13^a, 13^b. The concaved upper surface 12^c of extension 11^a bearing against convex rear surface of latch 13, of course, limits the upward movement of trigger 11. The 5 spring 16 is bowed, as indicated, intermediate its end.

From the foregoing description taken in connection with the accompanying drawing the novel features and advantages of my 10 safety hook are believed to be readily apparent. For instance, when the trigger member is pressed inwardly the locking member 13 is free to be moved by the bails either inwardly or outwardly. There is no possibility of the 15 latch member bails jamming. Furthermore, the forward ends of the ears 4, as indicated at 4^a, provide shoulders substantially transverse to the axis of the body 2. Thus, any pressure of the bails in the hook recess due to 20 relative vertical movement will engage such shoulder 4^a rather than the latch 13, thus, relieving the same of considerable strength.

While I have described and illustrated the 25 preferred embodiment of my invention, it is to be understood that the same is not limited thereto, but is susceptible of considerable change and modification within the spirit and scope of the subject matter claimed herein- 30 after.

Having thus described my invention, what I claim as new and desire to secure by Letters Patent is:

1. A safety hook of the class described comprising a body portion having a groove opening from one edge, a trigger member movably located in said groove and confined therein, one end of said body having a hook recess provided with an upwardly extending bill, a 35 latch element for closing said hook recess, and said latch element and trigger having cooperating shoulders which when the trigger element is in effective position serves to prevent movement of the latch member in either direction beyond said bill.

2. A safety hook of the class described comprising a body portion having a groove opening from one edge, a trigger member movably located in said groove and confined thereto, one end of said body having a hook recess provided with an upwardly extending bill, a 40 latch element for closing said hook recess, and said latch element and trigger having cooperating shoulders which when the trigger element is in effective position serves to prevent movement of the latch member in either direction beyond said bill, means in said groove and engaging said trigger member for normally actuating the same to hold the latch in 45 recess closing position.

3. A device of the class described comprising a body having a hook recess at one end and a groove in one edge communicating with said recess, a latch member in said groove and pivoted to move in two directions, a trigger

member associated with said latching member and located in said groove, said latch and trigger members having cooperating shoulders on either side of said latch pivot and operable to maintain the latch in a position to close said recess and against movement in either direction, said trigger being pivoted to swing inwardly into said groove to clear its shoulders from the latch shoulders so as to permit movement of the latch in either direction.

4. A device of the class described having a hook recess and a bill for partially closing said recess, the wall of said recess inwardly and opposite to said bill being substantially transversely disposed with respect to the body of the device, a movable latch member adapted to close said recess, the free end of said latch member being free to move in opposite directions beyond the bill to allow access to said recess, and a trigger member normally tending to hold said latch member against movement when in closed position.

5. A hook having a recess, a latch member for closing said recess, said latch member being movable both inwardly and outwardly to uncover said recess and means for locking said latch member against either inward or outward swinging movement when in closed position.

6. A hook having a recess, a latch member for closing said recess, said latch member being movable both inwardly and outwardly to uncover said recess and spring actuated means for locking said latch member against either inward or outward swinging movement when in closed position.

In testimony whereof I affix my signature.
JOSEPH F. MOODY.
